Inventor:

Paul Seiler

By his Ally, S. John Colton

UNITED STATES PATENT OFFICE.

PAUL SEILER, OF SAN FRANCISCO, CALIFORNIA, ASSIGNOR OF ONE-HALF
TO ANDRES NÚÑEZ, OF SAME PLACE.

AUTOMATIC TELEGRAPH SIGNAL-BOX.

SPECIFICATION forming part of Letters Patent No. 269,124, dated December 12, 1882.

Application filed August 18, 1882. (No model.)

To all whom it may concern:

Be it known that I, PAUL SEILER, a citizen of the United States, residing in the city and county of San Francisco, in the State of California, have made and invented certain new and useful Improvements in Automatic Telegraphic Signal-Boxes; and I do hereby declare that the following is a full, clear, and exact description of the same, reference being had to the accompanying drawings.

My invention relates to certain improvements in the signal setting and transmitting mechanism of telegraphic signal-boxes.

It consists in the construction and combinations hereinafter set forth and claimed.

The following description fully explains the nature of my said improvement and the manner in which I construct, apply, and use the same.

In the drawings herein referred to by figures and letters, Figure 1 is a perspective view of a signal-box constructed in accordance with my invention, the front of the case having the usual dial, and the index or pointer being removed from the signal-wheel hub to expose the parts. Fig. 2 is a detail view of the multiple-signal wheel that is fixed to and moved by the index on the outside of the box. It also shows the fixed bridge-piece that contains the signal number of the box. Fig. 3 is a side view of Fig. 2. Figs. 4 and 5 are detail views of the swinging arm and its contact-point, also of the automatic circuit-closer that permits passage of the current through the swinging arm in one direction of its movement and "short-circuits" the arm in the other direction.

The setting and transmitting mechanism consists of a signal-wheel, A, mounted loosely upon a stud, b, that projects from the back plate, X, of the box, and a pivoted vibrating or swinging arm, B, fixed on a shaft, C, and connected with a clock-work mechanism, D', of such character that when the arm is turned upward, or in what I shall term its "forward" direction, the shaft C is caused to wind up a coil-spring, d, and when released the shaft C is rotated in the opposite direction, and the arm B is brought back by the reaction of the spring and at the required rate of movement by the retarding ac-

tion of the clock-work. This manner of working the arm C is not new, as the same device is applied to the index or pointer in boxes of other construction where a wheel carrying signal characters in its rim is caused to turn by such spring device backward and in contact with a spring-point.

In my improved construction the signal-plate is independent of the transmitting mechanism, and is free to be turned in either direction and to remain set, if required, at any particular signal as long as desired.

The plate A has on one side a hub, from which radiate a number of ledges or tracks that stand out from the face of the plate to form narrow raised surfaces a a, &c. The ledges extend from the center outward to the circumference, and while placed in radial lines they are also arranged on curves that are part of a circle of a diameter equal to the length of the arm B from the axis C to its contact-point b. Each one of these ledges has a number of teeth and notches or elevations and depressions, the arrangement and relation of which determine the character of the signal on each one, and as many ledges can be arranged on a plate as may be desired, as they can be placed in very close order without interfering with the proper production of signals. This construction gives a signal-plate capable of containing a great number of signals.

Concentric with the axis C of the arm B and in proper relation to the wheel A, as shown, I place a fixed track or bridge-piece, E, over which the point of the arm B is carried on both its upward and its return or downward movement. This bridge-piece is fixed to the base X of the box, and is formed on a curve having its center at the center of rotation of the arm C. Any one of the radial ledges a when brought into line with this bridge therefore forms a continuation of it, because they are all struck with a radius equal to that of the curved bridge, and the axis of the plate A is located on the curve having this point C for its center.

One of the binding-posts, M, is in electric contact with the back plate, X, so that the bridge E is in connection with the line y; but

the frame D of the shaft C and clock-work D' d' are insulated from the box, so that the other line, z, being attached to the plate D, the current is taken through the arm B. This wire 5 z leads from the binding-post M' to the spools P, and thence down to the plate D, the circuit being thus through the magnet and plate to the arm, and thence to the bridge E. The normal condition of the current is a closed 10 one, as when the arm B is not in operation it rests upon the part e of the bridge E.

To prevent contact during the upward movement of the arm when it is being brought into position to be acted on by the signal-ledge a 15 on the plate A, the arm B is taken out of the circuit by the short-circuit device, shown in Figs. 4 and 5 of the drawings. This consists of the fixed contact-point q, projecting upward from the binding-post M', and a similar 20 point or finger, s, carried on the shaft C. Movement of the finger with the shaft as the crank is turned is effected by friction, for which purpose a split concave washer, A', placed on the shaft C, is held against the hub or center s', 25 from which the finger projects. In the position of the arm B when not in action the two points q s are out of contact, and the two are placed in such relation to each other that as the arm E is turned upward the finger s is 30 moved away from the fixed stop n, and is pressed against the point q. This contact is maintained as long as the upward movement continues; but as soon as the crank is released the spring reacts, and the arm is moved back 35 over the ledge a, separating the points q s and breaking the short circuit. The arm B is then in the circuit again, and its backward movement over the ledge a and the bridge E then gives the signal, first from the wheel A and 40 then from the bridge E.

It will be evident that the circuit through the wheel A, arm B, bridge E, and the magnet can be taken in several ways. In that given in Fig. 1 the circuit is in either direction 45 through the wire y, the base X, the bridge E, arm B, to the plate D of the clock-work mechanism; thence by the wire z' to the magnet; thence by wire z² out to the line z. The point q is in electric connection with the 50 base X of the box, by which the short circuit is made to cut out the arm B when the two points q s are brought together by the upward movement of the arm.

The simplicity of this short-circuit device 55 will be apparent. The manner of moving and holding the point s by friction accommodates the difference in movement required by the arm B, and no spring or auxiliary mechanism is necessary to operate the point s.

In connection with this transmitting mechanism, I provide a return-signal device operated directly from the armature of the magnet. This consists simply of an armature, T, hinged to the base of the box between brackets m m 60 in position to stand away from the poles of

the magnets, and to take this position when released from the magnets. This can be effected either by the gravity of the armature itself or by the additional assistance of a light spring, t. To its lower end a striker, U, is fixed in 70 such position that as the armature is drawn to the magnet the head of the striker is brought with force against a gong, V, and a signal is produced. At such time, also, a short circuit is made to cut out the magnet and restore the 75 armature to its first position. This short circuit consists of the wire w, leading from the wire z to one contact-point, w', and a spring, w², carried by the end of the armature T, forming another contact-point. Thus when a return-current is sent back from the receiving-station to the box, the magnet attracts the armature T and a signal is given, while the armature is instantly thrown back by the action of the short circuit w' w². 80

These several improvements reduce the expense of manufacture of such boxes, while at the same time they add to the simplicity and effectiveness of their operation. The multiple-signal plate is left at any particular signal as 90 long as desired, which is an advantage. The arrangement of the fixed signal-bridge and the mode of operating the transmitting-arm are also an improvement.

Having thus fully described my invention, 95 what I claim, and desire to secure by Letters Patent, is—

1. In a telegraphic signal-box, the signal plate or wheel A, having the radial ledges a a, mounted and capable of rotation upon an axis, 100 a means for rotating the said wheel from the outside of its inclosing box, and the swinging arm B, moving from a center, c, a means for rotating the said arm, and a short circuit to cut out the said arm from the circuit in one 105 direction of its movement over the signal-ledges a, and to restore it at the reverse movement, all combined to operate as set forth.

2. The multiple-signal wheel A, having the radial ledges a a, which are set on curves of 110 equal radii to spring uniformly from the center to circumference of the wheel to come in line with a fixed bridge on the same curve, in combination with said bridge, all constructed and applied to operate substantially as de- 115 scribed and shown.

3. In an automatic signal-box, the combination together of the multiple-signal wheel A, the fixed bridge E, the arm B, carrying the contact-point and operated by the shaft C, the 120 crank and clock-work mechanism, and the short-circuit points q s, substantially as described.

4. In an automatic alarm-box, the combination, with the swinging arm B, having movements as described, of the curved bridge E, carrying a fixed signal, and arranged relatively to the center of motion of the arm B, substantially as described. 125

5. The combination together upon a sup- 130

porting-base, X, of the automatic transmitting and return signal mechanism, consisting of the multiple-signal wheel A, having radial tracks or ledges a a , and the stationary bridge E, placed relatively thereto, as described, the swinging transmitting-arm B, and its operating mechanism C D d d ', insulated from the base, the short-circuit points q s , the electromagnet P, pivoted armature T, and striker, and

the short circuit w w' w^2 , all as described, to operate together, as set forth.

Witness my hand and seal.

PAUL SEILER. [L. s.]
